(57) **CLAIM**

The ornamental design for a glucose meter, as shown and described.

DESCRIPTION

FIG. 1 is an upper perspective view of a first embodiment of a glucose meter;

FIG. 2 is a lower perspective view of the glucose meter shown in FIG. 1;

FIG. 3 is an upper view of the glucose meter shown in FIG. 1;

FIG. 4 is a lower view of the glucose meter shown in FIG. 1;

FIG. 5 is a left view of the glucose meter shown in FIG. 1;

FIG. 6 is a right view of the glucose meter shown in FIG. 1;

FIG. 7 is a front end view of the glucose meter shown in FIG. 1;

FIG. 8 is a rear end view of the glucose meter shown in FIG. 1;

FIG. 9 is an upper perspective view of a second embodiment of the glucose meter;

FIG. 10 is a lower perspective view of the glucose meter shown in FIG. 9;

FIG. 11 is an upper view of the glucose meter shown in FIG. 9;

FIG. 12 is a lower view of the glucose meter shown in FIG. 9;

FIG. 13 is a left view of the glucose meter shown in FIG. 9;

FIG. 14 is a right view of the glucose meter shown in FIG. 9;

FIG. 15 is a front end view of the glucose meter shown in FIG. 9; and,

FIG. 16 is a rear end view of the glucose meter shown in FIG. 9.

The broken lines immediately adjacent to the shaded areas represent the bounds of the claim, and the remaining broken lines represent environmental subject matter; the broken lines form no part of the claimed design.

1 Claim, 12 Drawing Sheets
